No. 851,092.

PATENTED APR. 23, 1907.

L. JAMES.
HARNESS HOOK.
APPLICATION FILED MAY 1, 1906.

UNITED STATES PATENT OFFICE.

LEVI JAMES, OF COLUMBUS JUNCTION, IOWA.

HARNESS-HOOK.

No. 851,092.

Specification of Letters Patent.

Patented April 23, 1907.

Application filed May 1, 1906. Serial No. 314,666.

To all whom it may concern:

Be it known that I, LEVI JAMES, a citizen of the United States, residing at Columbus Junction, in the county of Louisa and State 5 of Iowa, have invented a new and useful Improvement in Harness-Hooks, of which the following is a specification.

My invention relates to improvements in harness hooks.

10 The object of my invention is to provide a hook of this character which is applicable especially to harness, and in which a leather tongue is formed integral with the strap to prevent the hook from being accidentally 15 disengaged from the ring or loop when it is in engagement.

Another object of my invention is to provide a more simple, cheap and effective hook of this character than has heretofore been 20 produced.

In the accompanying drawings: Figure 1 is a perspective view of my improved hook as attached to a trace carrier; Fig. 2 is an enlarged perspective view of the hook disengaged from the trace carrier; Fig. 3 is a perspective view of Fig. 2, showing the leather tongue thrown upwardly; Fig. 4 is a transverse sectional view taken on the line $x-x$ of Fig. 2; and Fig. 5 is a longitudinal sectional view taken on the line $y-y$ of Fig. 2.

Referring now to the drawings, 1 represents the strap to which my improved hook is attached. The said strap, as shown, is of a double form having its looped end 2 passing 35 through a ring 3 and the two ends 4 and 5 stitched together as shown at 6. While I have shown the strap as of a single piece and doubled, as described, it will be understood that the same could be in the form of two 40 straps stitched together, or it could have an additional strap stitched to any part of the harness to which my hook is to be applied. The straps, adjacent each edge, are provided with a row of stitching 7 which extends clear 45 to the end of the strap. The upper end 4 of the strap, on the inside of the stitching, is cut longitudinally of the strap and forms a tongue 8 at the end of the strap which is loose, as clearly shown in Fig. 3 of the 50 drawings. The said tongue being cut, as

shown, leaves a central longitudinal channel 9 between the narrow strips 10 left on the outside of the two rows of stitching. Within this channel is a plate 11 which is riveted to the lower strap 5 by means of rivets 12. The 55 said plate is of a length greater than the channel 9, so that the inner end 13 of the plates extends between the upper and lower straps 4 and 5 for rigidly securing the plate to the straps. The outer end of said plate is flush 60 with the ends of the strap or straps, whichever it may be, and is provided with an upwardly and inwardly turned end 14 which forms a hook and is adapted to hook into the trace carrier 15. 65

While I have shown and described my hook applied to a trace carrier, it will be understood that the same can be as readily applied to a ring or loop of almost any construction. 70

The tongue 8, as clearly shown, does not extend to the end of the hook, but is of a length sufficient to extend considerably under the rearward end of the hook 14, and thus the said tongue serves as a means for 75 preventing the hook from being disengaged from the carrier or ring to which it is applied. The lower strap under the plate 11, adjacent the hook, is provided with a loop 16 of leather under which the tongue 8 passes, the 80 said loop being of such a size that it frictionally engages the tongue and holds the same within the hook under the normal tension thereof and thus the hook is held against accidental disengagement with the carrier, ring 85 or loop.

In order to insert or remove the hook from the carrier or ring, the tongue 8 is moved within the loop until the outer end is brought from within the hooked member, so as to 90 remove or insert the carrier or ring, the loop frictionally holding the tongue in its normal position.

Having thus fully described my invention, what I claim as new and desire to secure by 95 Letters Patent, is:

The combination with a double strap stitched together at each edge by a row of stitching, the upper strap cut on the inner side of each row of stitching and forming a 100

tongue, a hooked member secured within the channel formed by the removal of the tongue, the said tongue being adapted to pass within said hooked member, and a loop secured to the lower strap adjacent the hook, and through which the tongue passes.

In testimony whereof I have signed my

name to this specification in the presence of two subscribing witnesses.

LEVI JAMES.
